UNITED STATES PATENT OFFICE.

WILLIAM A. SEXTON, OF MEDFORD, MASSACHUSETTS.

SHEET-METAL CAN.

1,009,443.

Specification of Letters Patent. Patented Nov. 21, 1911.

Application filed June 14, 1911. Serial No. 633,152.

To all whom it may concern:

Be it known that I, WILLIAM A. SEXTON, a citizen of the United States, and resident of Medford, in the county of Middlesex and 5 State of Massachusetts, have invented certain new and useful Improvements in Sheet-Metal Cans, of which the following is a specification.

This invention relates to sheet metal cans 10 having flat tops, the can top having a tubular nozzle through which its contents may be inserted and removed. A sheet metal cover is provided to close the nozzle, the cover having a flange which has a close frictional fit on the periphery of the nozzle and requires the application of a considerable 15 degree of force to apply the cover.

The invention has for its object to enable 20 the nozzle to be supported while the cover is being applied thereto in such manner that the pressure exerted on the cover will not distort or press the flat top of the can inwardly.

The invention consists in the improvements 25 which I will now proceed to describe and claim.

Of the accompanying drawings forming a 30 part of this specification,—Figure 1 represents a top plan view of a portion of the can embodying my invention. Fig. 2 represents a section on line 2—2 of Fig. 1. Fig. 3 represents a side elevation of a portion of the top of the can, parts of the nozzle and cover being shown in section. Fig. 4 represents a sectional view of a modification.

The same reference characters indicate the 35 same or similar parts in all the figures.

In the drawings, 12 represents a flat top 40 of a sheet metal can which may be of any desired form, the top being provided with a circular opening 13 which is surrounded by a nozzle suitably secured to the top and projecting upwardly therefrom. The nozzle is composed of an inner or base portion 14 at- 45 tached to the top 12, an outer portion 15 of greater diameter than the inner portion, and an intermediate connecting portion 16 which constitutes a shoulder between the inner and outer portions.

50 17 represents the cover which is a flat disk adapted to be seated on the outer end of the nozzle, said outer end constituting a seat for the inner side of the cover, a packing disk 18 of compressible material such as card- 55 board being preferably applied to the inner surface of the cover and formed to bear on

the outer end of the nozzle. The cover is provided with a cylindrical flange 17^a which is formed to have a close frictional fit on the periphery of the portion 15 of the nozzle, 60 said periphery constituting a flange seat. The outer end of the nozzle is preferably contracted and constitutes a cover seat located within the margin of the packing disk 18. 65

Owing to the fact that the flange 17^a tightly fits its seat on the nozzle, a considerable pressure is required to force the cover and its flange to place on the nozzle. To prevent this pressure from buckling the flat 70 top 12 inwardly, a supporting device is engaged with the shoulder 16 as indicated by dotted lines in Figs. 1 and 2, said device as here shown being a pair of nippers having segmental jaws 19 adapted to bear on the 75 portion 14 of the nozzle immediately below the shoulder.

In applying the cover to the nozzle, the supporting device is held against the shoulder 16 in such manner as to resist the downward pressure exerted while the cover flange is being forced to place on its seat, the supporting device being then removed. 80

The shoulder 16 is preferably tapered or inclined as shown by Figs. 2 and 3, and its 85 base portion where it joins the portion 14 of the nozzle is lower than the inner edge of the flange seat, so that the flange may be forced to place while the nozzle is supported by the device 19 without being obstructed by said device. 90

The flange 17^a may be provided with an aperture 20 extending partly across it, the lower edge of the flange extending continuously across the aperture and forming a narrow portion 17^b adapted to be severed by a cutting tool to permit the expansion of the flange and the removal of the cover. 95

Fig. 4 shows a modification in which the inner and outer portions 14^a and 15^a of the 100 nozzle are of the same diameter, and are connected by an outwardly projecting peripheral bead formed on the nozzle between said portions. The under side of said bead forms a shoulder 16^a which is the equivalent of the shoulder 16 and is adapted to bear on the jaws 19 when the cover is being forced to place on the nozzle. 105

The can top 12 is flat and unobstructed; that is to say, it has no upwardly projecting portions to interfere with the application of the jaws 19 to the shoulder 16 or 16^a, said 110

shoulder being sufficiently elevated above all parts of the top to enable the jaws to be interposed between the shoulder and the top so that the nozzle may be located close to one or more sides of the can as shown by Fig. 1.

I claim:—

A sheet metal can having an unobstructed flat top, a tubular nozzle comprising an inner cylindrical portion attached to the can top, an outer cylindrical portion, and an intermediate connecting portion forming a shoulder located between the inner and outer portions and elevated above the top sufficiently to permit a supporting device to be interposed between the shoulder and top,

the periphery of the said outer portion constituting a cover flange seat while its outer end forms a cover seat, and a cover formed to bear on the cover seat and provided with a flange projecting from its margin and formed to have a close frictional fit on the said flange seat, said shoulder being adapted to be engaged by a supporting device resisting the pressure which forces the flange onto its seat.

In testimony whereof I have affixed my signature, in presence of two witnesses.

WILLIAM A. SEXTON.
